COMBINATION FLASHLIGHT AND FISHING POLE HANDLE

Palmerino C. La Falce, Buffalo, N. Y.

Application November 30, 1950, Serial No. 13,209

Term of patent 14 years

(Cl. D31—4)

To all whom it may concern:

Be it known that I, Palmerino C. La Falce, a citizen of the United States, residing at Buffalo, in the county of Erie and State of New York, have invented a new, original, and ornamental Design for a Combination Flash Light and Fishing Pole Handle, of which the following is a specification, reference being had to the accompanying drawings, forming a part hereof.

In these drawings:

Fig. 1 is an elevational view of one side of a combination flash light and fishing pole handle, embodying my new design.

Fig. 2 is a top plan view thereof.

Fig. 3 is a bottom plan view thereof.

Fig. 4 is an elevational view of the front end thereof.

Fig. 5 is an elevational view of the rear end thereof.

I claim:

The ornamental design for a combination flash light and fishing pole handle, substantially as shown.

PALMERINO C. LA FALCE.
